UNITED STATES PATENT OFFICE.

WACLAW WOLSKI, OF SCHODNICA, AUSTRIA-HUNGARY.

DEEP-BORING APPARATUS.

SPECIFICATION forming part of Letters Patent No. 699,273, dated May 6, 1902.

Application filed September 10, 1900. Serial No. 29,568. (No model.)

To all whom it may concern:

Be it known that I, WACLAW WOLSKI, a subject of the Emperor of Austria-Hungary, residing at Schodnica, in the Province of Galicia, in the Empire of Austria-Hungary, have invented certain new and useful Improvements in Deep-Boring Apparatus; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The present invention relates to apparatus for boring deep wells, sinking deep shafts, and more especially to that type in which the water used to wash the spoils out of the bore-hole is utilized to drive the tool, but not in the ordinary manner.

The novelty in the operation of the device consists in operating the tool by water shock, the same principle being used in the well-known hydraulic ram as a means for lifting water.

Referring to the drawings, in which like parts are similarly designated, Figure 1 is a vertical section of a hole with the boring apparatus therein in section. Fig. 2 is a similar view showing the preferred construction of apparatus; and Figs. 3 and 4 are fragmentary sectional views illustrating a modified construction and an arrangement of the valves shown in Figs. 1 and 2, showing elastic valves.

In this apparatus the working parts are at the end of the bore and attached to the bore-tubes *m*, through which the water for driving the tool and flushing out the bore-holes is driven in the usual manner by a suitable pump, (not shown,) the structure of the operating parts at the ends of the tube *m*, however, being of a different nature and operating on a different principle than the usual water-driven tools, and this apparatus is constructed as follows:

Referring to Fig. 1, the end section of pipe *m* projects into an air-chamber *a*, larger than the tube *m*, so as to form a trap containing an air-cushion, the utility of which will be explained hereinafter. Continuing from the

air-chamber *a* is the hollow element or tube *b*, preferably made heavier than the tubes *m* and on the end of which is secured the driving-cylinder *c*. This cylinder *c* is closed at its end by a guide-plug *o*, here shown as screwed into the end of the cylinder and provided with a central opening for the piston-rod *f*. In the cylinder is the hollow piston *d*, whose head is provided with water by-pass ports *h'* in its upper end, the lower end of said piston being continued as the hollow piston-rod *f*, preferably, though not necessarily, formed in one piece with the piston, and which projects through the screw-plug *o* at the bottom of the cylinder *c*. Into the end of the hollow piston-rod *f* is screwed the hollow cutting-tool *g*, provided with water-outlets *g'*, said tool resting on the sole of the bore-hole of such a size as to cut a hole larger in diameter than the cylinder and of any desired cutting contour. Between the piston and the screw-plug *o* and around the piston-rod is a coil-spring *e*, the object of which is to return the piston and tool to its position ready to receive the driving blow. On the piston-head is carried a bracket *i'*, in which is guided the stem of the valve *i*, normally held retracted by a coil-spring *k* around its spindle and held between the bracket and nuts *l*. This valve controls the by-pass ports *h'*, formed in the piston-head, and the force required to close it is regulated by means of turning the nuts *l* to increase or decrease the tension of the spring.

The operation is as follows: The water is sent by the pump (not shown) down the hollow bore rod or tube *m*, passes through the valve-ports *h'*, interior of the piston *d*, piston-rod *f*, openings *g'* in the tool, and ascends on the exterior of the bore-tool, cylinder, and bore-rod, carrying with it the sludge, thus clearing the bore-hole of debris. The down column of water attains an increasing velocity, and the inertia will then increase sufficiently to force down the valve *i* against the stress of its spring *k* to automatically close the by-pass *h'*, thus suddenly cutting off the flow of water, and the inertia of the moving column will then be exerted on the closed valve and piston. The piston and tool will then be automatically forced down, overcoming the stress of the lifting-spring *e* to drive the tool *g* against the sole of the bore-

hole. As in the case of impact imparted to elastic rods, the sudden jar of the water produces in the lower part of the descending water column an increase in density, and consequently of pressure, which is transmitted upward as far as the air-chamber with the same rate of velocity that sound travels in water—that is, about fourteen hundred and fifty meters per second. In the air-chamber, between the surface of the air and water, reflection from the air-chamber takes place. The condensation is transformed here instantly into rarefaction, the effect of which is transmitted downward with the same velocity, thus gradually canceling by interference the condensation which hitherto existed, and when it has reached the bottom of the column produces there a sudden rarefaction of the same strength. At the same time the valve i opens by reason of the stress of its spring k , and the water again flows through the opening h , and the tool is returned to normal position by its spring e . The water column in the hollow rod b is again put in motion with an acceleration corresponding to its mass and to the pressure of the water in the air-chamber. After the lapse of a few moments the velocity of the water has again increased to such an extent that it will close the valve i to repeat the operations just described. In this way the boring-tool is caused to impart a succession of vigorous blows against the sole of the bore-hole at short intervals of time, the total effect of these strokes corresponding to the mechanical work accomplished by the pump. The number of strokes in the above apparatus can be easily regulated, as well as the force of each stroke. The pressure produced by the water is proportional to the velocity of the impact, and as this is identical with the velocity sufficient to close the valve, hence the pressure of the jar of the water can be regulated by regulating the amount of force required to seat the valve, which will be accomplished by regulating the tension of the spring k by means of nuts l . The duration of the stroke can, on the other hand, be regulated by regulating the length of the water column between the air-chamber and valve—that is, increasing or decreasing it. The duration of pressure will last for the length of time required for the elastic wave to travel the length of this column and back.

In Fig. 2 the valve controlling the water is not secured to the piston, and consequently does not reciprocate with it. The cutting-tool g^2 is made solid, and a solid piston-rod f^2 and piston d^2 are secured to it. The bottom of the cylinder-casing n is closed by a guide-plug o^2 , provided with water-outlets o^3 and a central bore, in which is guided the piston-rod f^2 . This piston-rod f^2 is provided with a collar f^3 , between which and the screw-plug o^2 and around the piston-rod f^2 is a coil-spring e^2 to retract the cutting-tool. In the casing

n is the cylinder c' , projecting from the conical valve-seat that forms its upper end and provided with water-passages h^2 . A bracket i^2 is rigidly connected to the casing n . A spring k^2 and nuts l^2 are for the same purpose as described in reference to Fig. 1. The valve i^3 is a conical ring-valve and controls the ports h^2 in the conical seat. The operation is on the same principle as that of Fig. 1. The water column is set in motion by the outflow through the ports h^2 , casing n , water-passages o^3 in the plug o^2 , and upward between the exterior of the boring-tool and cylinder and the walls of the bore-hole. When the velocity of the water is sufficient to cause it to overcome the resistance of the valve i^3 , this valve is forced on its seat. The inertia of the moving mass will drive the water through the center of the valve against the end of the bore-tool in the same manner as described with reference to Fig. 1. Instead of the valve shown in Fig. 1 I may use one consisting of an elastic plate o^4 , Fig. 3, made of rubber, elastic steel, or similar material.

Fig. 4 shows a ring-valve p of elastic material that can replace the valve i^3 , Fig. 2.

Having now described this invention, what I claim as new therein, and desire to secure by Letters Patent, is—

1. In a water-actuated boring apparatus, a cylinder, a reciprocable tool, a by-pass, means for sending water to said cylinder and by-pass, a valve controlling the by-pass automatically closed by the force of the moving water, whereby the inertia of the column of water is imparted to the tool, substantially as described.

2. In a boring apparatus, a cylinder, a reciprocable tool, a by-pass, hollow bore-rods to send water to said cylinder and by-pass, a valve controlling the by-pass automatically closed by the force of the moving water to cause the inertia of the moving column of water to drive the tool and a suitably-located air-chamber to prevent the force of impact of the water from being translated to the bore-rods, substantially as described.

3. In a water-actuated boring apparatus, a cylinder, a reciprocable tool, a by-pass, hollow bore-rods to send water to said cylinder and by-pass, a valve controlling the by-pass, automatically closed by the moving water to cause said water to act by inertia on the tool, means for determining the length of time that the water effectively acts on the tool and means for determining the number of blows per unit of time, substantially as described.

4. In a water-actuated boring apparatus, a cylinder, a spring-retracted reciprocable tool, a by-pass, hollow bore-rods to send water to said cylinder and by-pass, a valve controlling the by-pass automatically closed by the force of the moving water to cause the inertia of the moving column of water to drive the tool and an air-chamber located above the cylinder on the end of the bore-rod to prevent the

force of impact of the water from being translated to the bore-rods, substantially as described.

5. In a water-actuated boring apparatus, a cylinder, a reciprocable tool, a by-pass, a hollow bore-rod to send water to said cylinder and by-pass, a valve controlling the by-pass automatically closed by the force of the moving water to cause the inertia of the moving column of water to drive the tool, an air-chamber and a weighted element forming part of the bore-rod, substantially as described.

6. In a water-actuated boring apparatus, a cylinder, a reciprocable tool, a by-pass, a valve controlling the by-pass, a hollow bore-rod, and an air-chamber and a heavy hollow element between the end of the bore-rod and cylinder to prevent shock being translated to the bore-rod and to determine the number of impacts per unit of time, substantially as described.

7. In a water-actuated boring apparatus, a reciprocable spring-retracted tool, a casing, a cylinder having an upper conical end secured to the casing and provided with by-pass ports, a yieldingly-held valve controlling the by-pass ports and having a central passage over the cylinder leading to the tool, and means for preventing the translation of shock to the rod, substantially as described.

8. In a water-actuated boring apparatus, a hollow bore-rod, an air-chamber, the end of the bore-rod projecting into one end of said chamber to form an air-trap, a casing, an ele-

ment connecting one end of the casing and air-chamber that determines the duration of the shock imparted by the water, a cylinder in said casing having a flaring end, by-pass ports in said flaring end, a spring-retracted piston in said cylinder, a tool carried by the piston and a ring-valve controlling the by-pass ports automatically closed by the moving water to direct the inertia of the moving column through the valve against the piston, substantially as described.

9. In a water-actuated boring apparatus, a hollow bore-rod, an air-chamber, the end of the bore-rod projecting into the upper end of said chamber to form an air-trap, an open-ended cylinder, an enlarged conical end to said cylinder, by-pass ports in said conical portion, a casing surrounding the cylinder, a plug in the end of the casing provided with openings to admit water to the sole of the bore-hole, a piston in said cylinder, a tool secured to said piston, a collar f^3 , a spring between the collar and plug and a spring-retracted ring-valve controlling the by-pass ports automatically operated by the water to direct the moving column against the piston to drive the tool, substantially as described.

In testimony that I claim the foregoing as my invention I have signed my name in presence of two subscribing witnesses.

WACLAW WOLSKI.
